BUTTON SEWING MACHINE

Lawrence G. Burkey, Cresson, Pa., assignor to S. Liebovitz & Sons, Inc., Myerstown, Pa., a corporation of New York

Application January 22, 1941, Serial No. 375,484

18 Claims. (Cl. 112—113)

This invention relates to improvements in sewing machines and has particular reference to a button sewing machine.

An object of the invention is to provide an improved machine of practical construction wherein a transfer mechanism is operable between a button feeding device and the button clamp of the machine to initially adjust a button at said device to a predetermined position relative to the needle of the machine so that when the mechanism is operated to deliver said button to the clamp, each opening or hole in the button will be vertically aligned with said needle to permit its passage therethrough as the sewing operation progresses.

Another object is to control the operation of the button clamp in such manner that when the same is raised to release a stitched button, the upward movement of the clamp will be interrupted, following the release of said button, to permit a transfer mechanism to deliver a succeeding button to the clamp.

A further object resides in the control of the transfer mechanism whereby, as the same is returned to the feeding position, after delivery of a button to the clamp, it will have a movement in successively different planes, the last of which will position a button-carrying element of said mechanism beneath another button at the feeding device.

A still further object is to provide an improved button feeding device of simple and practical construction which will enable buttons to be fed to a delivery position of said device in such manner that when the button is picked up by the transfer mechanism and delivered to the button clamp of the machine, said button will be in proper position for application to the fabric or garment to which it is to be sewed.

The above and other objects will appear more clearly from the following detailed description when taken in connection with the accompanying drawings which illustrate a preferred embodiment of the inventive idea.

In the drawings—

Figure 1 is a side elevation, partly in section, of a button sewing machine embodying the novel characteristics of the present invention.

Figure 1A is a plan view of a thread guide operating means by which said guide is adjusted from its normal operating position during the transfer of a button from the feeding device to the button clamp of the machine.

Figure 2 is a side elevation, partly in section, taken from the opposite side of Figure 1.

Figure 3 is a horizontal section taken substantially on the line 3—3 of Figure 2.

Figure 4 is a section taken substantially on the line 4—4 of Figure 3.

Figure 5 is a section substantially on the line 5—5 of Figure 3.

Figure 6 is an elevation of a button guiding device shown in plan view at the upper portion of Figure 3.

Figure 7 is an elevation of the button feeding mechanism with the casing in section.

Figure 8 is a top plan view thereof.

Figure 9 is a section on the line 9—9 of Figure 7, and

Figure 10 is a detail sectional view of a portion of the feeding mechanism taken on the line 10—10 of Figure 7.

Briefly, the invention is shown in its adaption to a standard type of button sewing machine comprising the bed plate 15 supporting the overhanging arm 16 in which the main shaft 17 operates, among other elements, the needle 19. Also mounted in the arm 16 is the button clamp-operating rod 18. Above the bed plate there is mounted a button clamp of known construction, indicated by the numeral 20, the general operation of which follows the standard practice in its longitudinally reciprocating and transverse movements relative to the bed plate when stitching a button with four holes, and in its vertical movement when releasing the stitched button. Attached to the bed plate 15 is a vertically disposed supporting plate 21 the upper portion of which carries a button feeding device 22 from which buttons are fed downwardly through a chute 23 to a delivery position, indicated generally at 24. Operating between said delivery position and the button clamp 20 is a transfer mechanism embodying certain of the novel characteristics of the present invention.

The machine illustrated in the accompanying drawings is of the type which automatically stops at the conclusion of a stitching operation and which is again set in motion by the depression and release of a foot treadle 25 (Figure 2). The automatic stopping of the machine and its restarting is under the control of the well-known mechanism, generally indicated by the numerals 26 and 27 (Figure 1) which is utilized to shift the drive belt 28 back and forth between the drive and idler pulleys 29 and 30 on the main shaft 17 of the machine. Since this mechanism does not constitute any part of the present invention, a detailed description thereof is deemed unnecessary. Likewise, the horizontal reciprocation and

transverse shifting of the button clamp 20 is controlled by a well-known mechanism including the cams 31 and 32 mounted on the shaft 33. The cam 31 is engaged by a roller 34 to longitudinally reciprocate the clamp 20, while a roller 35 engages in the groove 36 of the cam 32 to control, in a well-known manner, the transverse shifting of said clamp through the connection, generally indicated by the numeral 37. It will be understood that one revolution of said cams about the shaft 33 completes a stitching operation and the mechanism 26, 27 then becomes effective to shift the belt drive 28 to the idler pulley. At the conclusion of this operation, the parts of the machine are in the position as shown in the various figures of the drawings.

A brief description of the conventional button clamp will suffice for an understanding of its construction and operation in conjunction with the transfer mechanism. Said clamp comprises an arm 33 having one end mounted upon a movable block 39 and extending horizontally therefrom in the direction of the needle 19. Pivoted to the undersurface of the arm 33 are the cooperating clamping jaws 40 which extend diagonally downward from said arm and have disposed therebetween the stop member 41 against which a button 42, held between said jaws, abuts when in proper position for a stitching operation. The slotted spread plate 43 is slidably carried by the inner end of the stop member 41 and the slots of said plate are engaged by the pins 44 depending from the jaws 40. The inner end of the stop 41 is attached to a slide 45 which moves in a longitudinal slot 46 in the arm 33. This slide 45 is connected, by coil spring 47, to a pin 48 at the forward end of the arm 33 and said spring is effective to normally retain the clamping jaws 40 in operative position and to restore said jaws to such position after the slide 45 has been moved rearwardly to spread the jaws through the instrumentality of the spread plate 43. In order to retract the slide 45 to spread the jaws, there is pivotally mounted on the arm 33 the opening bell-crank lever 49 which, when depressed as will presently appear, moves the slide against the tension of the spring 47 to open the jaws. A leaf spring 50 bears against the upper surface of the arm 33 to maintain the clamp in its horizontal position during the stitching operation and to restore said clamp to said position after the clamp has been raised to release a stitched button therefrom and receives another button to be stitched from the transfer mechanism.

At the conclusion of a stitching operation, the operator of the machine depresses the treadle 25 and may immediately release the same. This depression of the treadle initiates the operation of transferring a button from the delivery position 24 to the jaws 40 of the clamp and the restoration of the treadle under the influence of the spring 51 automatically starts the stitching operation upon the transferred button. When the treadle 25 is depressed a link 52 connected thereto, and to the arm 53, pulls downwardly upon said arm to rotate the shaft 54 in a clock-wise direction, as viewed in Figure 2. This shaft carries the main cam 55 which is provided in its periphery with a recess 56 in which is disposed one end of a rocker arm 57 pivotally mounted upon the supporting plate 21. The other end of said arm is joined by a link 58 to a rocking lever 59 pivoted at 60 upon the top of the arm 16 of the machine. An extension 61 of said lever connects

the same to the control mechanism 26, 27 whereby this mechanism is set by the depression of the treadle so that the next stitching operation will be initiated when the lever 59 is restored to its normal position by the release and consequent elevation of the treadle 25. The rotation of the main cam 55 causes the wall of the recess 56 to elevate the end of the arm 57 engaged therein and thus produces a rocking of the lever 59. 5 Before said arm is entirely disengaged from the recess 56, it engages in a notch 62 formed in the wall of said recess, and this engagement produces a momentary interruption in the rocking of the arm 57, and consequently of the lever 59. This momentary interruption is utilized for the purpose of engaging a button being transferred with the jaws 40 of the button clamp 20, as will be later described in more detail. When the lever 59 is rocked about its pivot, the end thereof remote 10 from the link 58, and which is engaged with the upper end of the operating rod 18, becomes effective to lift said rod and this raising of the rod accomplishes the lifting of the button clamp during which upward movement the jaws 40 are first 15 spread to release the button which has just been sewed, and then immediately closed so as to receive another button from the transfer mechanism. The lifting of the clamp 20 by the rod 18 is effected through a block 63 on the lower end 20 of said rod engaging the bent upper end of the pin 48 at the forward end of the arm 33. At the beginning of the upward movement of the clamp, the opening lever 49 thereof contacts the lower end of a pivoted spring-pressed latch 64 carried 25 by the lever 65 pivoted on the stub shaft 66 supported by the plate 21. The engagement of the lever 49 with the latch 64 depresses the engaged end of said lever so as to rock the same about its pivot and thus retract the slide 45 of the button clamp to spread the jaws 40 thereof and thus release the sewed button 42 held between said jaws. During this action, the rotation of the cam shaft 54 (see Figure 1) is utilized to rock the lever 65 about its pivot through the medium of 30 a link 67 connecting said lever with an arm 68 on said shaft. This operation of the lever 65 moves the latch 64 out of engagement with the lever 49 whereupon the spring 47 becomes effective to restore the jaws 40 of the button clamp to their button-receiving and button-retaining position preparatory to the delivery of a button thereto by the transfer mechanism. While a button is thus being released, the rotation of the cam shaft 54 is also utilized to control the shifting of the thread guide 69 (Figure 1A) to a position where it will not interfere with the delivery of a button from the transfer mechanism to the clamp. To this end, a link 70 is connected to the arm 68 on the shaft 54 and also to another arm 71 on the shaft 72 journaled in the supporting plate 21. Thus, the rotation of the shaft 54 in a counter clock-wise direction, as viewed in Figure 1, results in a rotation of the shaft 72 in a clock-wise direction. The latter shaft carries an arm 73 connected to one end of a link 74, the other end of which is joined to an arm 75 pivoted on the undersurface of the block 63 and carrying the thread guide 69, so that as the arm 73 is turned with the shaft 72, a pull will be exerted upon the arm 75 to swing the same about its pivot and thus move the thread guide out of the way of the transfer mechanism as a button is delivered to the clamp 20.

In addition to the function just described, the

shaft 72 is also utilized to control the operation of a button guiding device shown at the upper portion of Figure 3 and in Figure 6. This device is employed for the primary purpose of securing a proper and predetermined spacing between the various buttons being sewed onto a fabric. Said device comprises a base plate 76 supported a distance from the needle 19. One end of said base plate is formed with a guide 77 by bending said plate as shown in Figure 6. An adjacent portion of the plate is also bent as at 78 and then turned under to form another guide 79 opposed to the guide 77 and forming a tapered opening therebetween for the reception of a sewed button 80 on the fabric 81. A slide stop arm 82 has one end normally straddling the opening between the guides so that the button 80 will engage said arm and thus limit the movement of the fabric by the operator in the direction of the arrows in Figure 3. By so doing, a predetermined distance between the button 80 and the next button to be sewed to the fabric will be established. The arm 82 is slideable in brackets 83 secured to the base plate and one of said brackets has adjustably attached thereto a fabric guide 84 against which an edge of the fabric 81 engages as it is moved along by the operator. An actuating member for the stop arm 82, in the form of an elongated plate 85, is adjustable along said arm and has one end 86 upturned to provide an abutment utilized in the momentary retraction of the arm 82 from its operative position at the guides 77, 79. To so retract said arm, the rotation of the shaft 72, previously described, is employed. To this end, a disk 87 on said shaft carries a pivoted spring-pressed lever 88 one end of which engages a stop pin 89 on said disk while the other end is disposed so as to engage the abutment 86 when the disk 87 is rotated. The engagement of said lever with said abutment will retract the stop arm from its position in the path of the button 80 and, at this moment of retraction, the operator moves the fabric along in the direction of the arrow in Figure 3 so as to pass the button 80 from between the guides 77, 79. The operator then continues to move said fabric, as described, until the button which has just been sewed, such as the button 82, enters the opening between said guides and contacts the stop arm 82 which has been restored to its operative position under the influence of the spring 90 after the lever 88 has cleared the abutment 86. Upon the return movement of the shaft 72 and disk 87, at the time the treadle is released and the main cam 55 is restored to normal, the lever 88 will be permitted to swing about its pivot and ride over the abutment 86, being restored to its normal position against the pin 89 by the spring 91 engaged with said lever.

Before proceeding further with the description of the various functions of the main cam 55, the construction of the transfer mechanism will be set forth. For this purpose reference is had particularly to Figure 4. This mechanism is shown as comprising a horizontally disposed housing 92 in the nature of a swinging arm from one end of which there projects upwardly a sleeve 93 constituting an axial portion about which the housing oscillates. An operating shaft 94 extends through the sleeve 93 and upwardly thereabove and carries at its lower end a gear 95. This gear drives two idler gears 96 and 97 the latter of which meshes with still another gear 98, all said gears being journaled within the housing. Directly above the gear 98 the housing is provided with an opening 99 in which is engaged a button-

carrying element 100 in the form of a disk. This element has extending upwardly therefrom two pins 101, which are adapted to engage in opposed openings or holes in a button 102 located at the delivery position 24 of the button feeding device. At said position, the button is held between two pivoted jaws 103 (Figures 3 and 5) which are connected by a spring 104 to yieldably hold said jaws closed about the button, said jaws spreading when the transfer mechanism extracts the button 102 from between the same. Secured to the sleeve 93 intermediate its ends is a collar 105 provided with an extension 106 to which is connected, by the ball joint 107, an operating rod 108 utilized to swing the housing 92 back and forth between the delivery position 24 and the button clamp 20, as will later be described in more detail. Interposed between a stationary abutment 109 surrounding the sleeve 93 and the undersurface of the collar 105, is an expansible coil spring 110 which exerts an upward pressure upon the collar, and consequently upon the sleeve 93 and the housing 92. At a certain stage of the operation of the transfer mechanism, that is when the housing is returning from the button clamp to the delivery position to pick up another button at said position, the housing 92 is depressed so that it will swing in two different horizontal planes during said movement. This depression of the housing is accomplished through the intermediary of a rocking lever 111 (see also Figure 2) pivoted at 112 to the vertical supporting plate 21 and engaged with the periphery of the cam 55, a stop 113 contacting said lever to maintain it in proper engagement with said cam. The control of the lever 111 by which the housing 92 is depressed will be presently described.

The purpose of lowering the housing 92 during the latter portion of its swinging movement toward the delivery position 24 is to locate the button-carrying element 100 beneath the button at said position so that the pins 101 will initially engage the undersurface of said button before they enter two opposed holes of said button, unless it so happens that when said element 100 is positioned beneath the buttons the pins thereof will directly align with said holes, in which instance the pins will immediately engage therein. It is at this time of the engagement of the pins with the undersurface of the button at the delivery position that the shaft 94 is rotated to also rotate the element 100. The amount of this rotation is predetermined and constant and is sufficient to enable the pins 101 to align with two of the holes in the button at some stage during the rotation of the button-carrying element. Due to this definite rotation, the element 100 will turn the engaged button, after the pins are in the holes, to a predetermined position relative to the needle 19 of the machine so that when said button is delivered to the clamp 20 its position will be such that the holes in the button will successively be vertically aligned with the needle 19 as the sewing operation progresses under the control of the cams 31 and 32. During the interval that the element 100 is located beneath the button, the spring 110 acts to exert an upward pull upon the housing 92 which will assure contact of the pins 101 with the undersurface of the button 102, and as soon as the pins 101 are registered with holes in said buttons, said spring 110 will act to impart a further slight upward movement to the housing 92 so that said pins will enter the holes of the button after which the latter will be rotated to its predetermined position. The

rotation of the shaft 94 is accomplished through the medium of a bevelled gear 114 secured to the shaft above the sleeve 93 and meshed with another bevelled gear 115 carried upon one end of the shaft 116 journalled in a bearing on the supporting plate 21. The opposite end of the shaft 116 carries a small bevelled gear 117 which engages a larger bevelled gear 118 loose on the shaft 33. Also loose on said shaft is a ratchet 119 engaged by a pawl 120 which is fixed to said shaft. Said shaft 33 is geared to the main shaft 17 of the machine in a conventional manner so that when said main shaft is driven through one complete revolution of the cams 31, 32, the pawl 120 will drive the ratchet 119 and gear 118 which are fixed to each other. The reduction between the gears 113 and 117 is such that the shaft 94 will cause the button-carrying element 100 to rotate something less than a complete revolution but sufficient to cause the pins 101 to register with the holes in the button. When the machine is first put into operation by introducing a supply of buttons into the delivery chute 23 of the feeding device, the transfer mechanism is located at the delivery position 24. It may be necessary at this time for the operator to manually depress the housing 92 so that the pins 101 of the button-carrying element will be located beneath the first button which is fed to the delivery position. This depression of the housing, against the tension of the spring 110 may be accomplished by simply grasping the housing and pressing it downwardly. It may be also necessary, at this time, to manually rotate the button-carrying element 100 so that the pins 101 will register and enter the holes in the button at the delivery position after the downward pressure upon the housing, just mentioned, is relieved. The means of rotation is accomplished through a hand wheel 121 the shaft of which extends through a bracket 122 and carries a bevelled gear 123 that meshes with the gear 114. By turning the wheel 121 in the proper direction, the shaft 94 will be rotated to secure the desired result of engaging the pins 101 in the holes of the button at the delivery position. When the shaft 94 is thus rotated, the shaft 116 is also turned by reason of its connection to the gear 114. However, this rotation of the shaft 116 merely turns the gear 118 and ratchet 119 freely about the shaft 33. The pawl 120 fixed on said shaft will ride over the teeth of the ratchet 119 as the latter is turned and said pawl will come to rest in engagement with one of said teeth after the pins 101 have been engaged in the holes of the button.

Returning now to the operation of the main cam 55, it will be recalled that the end of the arm 57 engaged with said cam had moved to a position wherein it was momentarily resting in the notch 62 of the cam. Just prior to this, a small cam 124, adjustably secured to the periphery of the cam 55, actuates a spring-pressed lever 125 which carries at its upper end a dog 126. The dog is moved to the left, as viewed in Figure 2, by the actuation of said lever and engages one end of a slide bar 127 movable in a bearing 128 upon the plate 21. The other end of said bar is joined to the adjacent end of the operating rod 108 which is connected to the collar 105 fixed on the sleeve 93 of the transfer mechanism. By forcing said rod 108 to the left, the sleeve 93 will be turned about the shaft 94 and consequently the housing 92 will start its movement in a horizontal plane from the delivery position 24 toward the button clamp 29, thus withdrawing the button

102 from said position and carrying the same toward said clamp. During this swinging movement, the momentary interruption in the upward movement of the clamp 20 takes place, due to 5 the notch 62 in the cam 55, and at the instant of interruption the button 102 is inserted between the jaws 49 of the clamp, which jaws have been previously closed as a result of the disengagement of the latch 64 from the opening lever 49 10 of the clamp and the consequent restoration of the jaws under the influence of the spring 47. With the button now deposited between the jaws, a further rotation of the cam 55 removes the end of the arm 57 from the notch 62 and thereby 15 further elevates the clamp 20. This movement of the clamp lifts the delivered button from the pins 101 of the button-carrying element so as to free said button from said element, as indicated in dotted lines in Figure 5. The instant that said 20 button is so freed, a pin 129 carried by an adjustable plate 130 on the cam 55 contacts and lifts the dog 126 out of engagement from the bar 127. Immediately, the spring 131 connecting the bearing 128 with the extension 106 of the collar 105 25 becomes effective to turn said collar, and consequently the sleeve 93, in the opposite direction from that described so as to start the return movement of the housing 92 and its button-carrying element 100 toward the delivery position 24. At a point during this return movement a cam 132 adjustably secured to the periphery of the main cam 55 engages the adjacent end of the rocking lever 111 to raise said end and lower its opposite end which is in engagement with 30 the collar 105 (Figure 4). This action forces the housing 92 downwardly to a lower plane, as previously referred to, so that the pins 101 of the button-carrying element 100 will be positioned beneath the next succeeding button at the delivery 35 position 24 and out of contact therewith when the housing has completed its return swinging movement. In order to insure the correct positioning of the button-carrying element beneath the button at the conclusion of the return movement of the transfer mechanism, a stop 133 (Figure 2) extends from the collar 105 and abuts against the supporting plate 21 when said mechanism has reached said position.

These operations having now taken place during the clock-wise movement of the cam 55 under the influence of the depression of the treadle 25, and the treadle having been released so that it will restore under the influence of the spring 51, the cam 55 will now start its return movement 50 in a counterclockwise direction. The cam 132 will first disengage from the end of the lever 111, permitting said lever to restore to the position of Figure 2 and thus relieve the downward pressure upon the collar 105. The spring 110 will thereupon force the housing 92 upwardly until the pins 101 engage the undersurface of the button at the delivery position. At the same time, the end of the lever 57 engaged with the cam 55 will enter the recess 56 and, under the influence 55 of a well-known spring (not shown) in the overhanging arm 16, the raised operating rod 18 will be lowered. This movement starts the restoration of the lever 59 to the position of Figure 2 and through the connection 61 of said lever of the mechanism 26, 27, the drive belt 28 is shifted to the pulley 29 and the main shaft 17 is started to perform another stitching operation. The starting of this operation does not occur, however, until the operating rod 18 has been fully 60 65 70 75

lowered and the clamp 28 has been restored to its operative position shown in Figure 1. Also at the start of the return movement of the cam 55, the pin 129 is withdrawn from engagement with the dog 126 permitting it to restore to its operative position, and the cam 124 is disengaged from the lever 125 so that the latter will also restore.

The action of the spring 131, in returning the transfer mechanism also forces the rod 108 and bar 127 back to the position of Figure 2 preparatory to the next reciprocation thereof by the dog 126 when the cam 55 is again operated. The restoration of the cam 55, and consequent reverse rotation of the shaft 54 imparts the necessary turning movement to the shaft 72 to swing the thread guide 69 back to its operative position, and the rotation of said shaft 72 also turns the disk 87 back to the position of Figure 6. At the conclusion of the return movement of the cam 55, the levers 57 and 59 will again assume the position of Figure 2 and the main shaft 17 will again be automatically operated by the control mechanism 26, 27 to perform another sewing operation upon the button which has just been deposited in the jaws of the clamp 28, thus completing a cycle of operation.

The feeding device illustrated in Figures 7 to 10, which is employed to feed buttons from the hopper 22 downwardly through the chute 23 to the delivery position 24, will now be described in detail. Said device comprises a rotatable drum 134 fixed upon a shaft 135 extending through the hopper, and said shaft is driven at a slow speed from a separate source of power such as an electric motor (not shown) through the medium of a pulley 136 loosely mounted on said shaft and operated by the drive belt 137, a clutch mechanism, generally indicated by the numeral 138, being utilized to drive the shaft from said pulley. The hopper 22 is formed therein at one side thereof with a recess or compartment 139 in which the drum 134 revolves and the remaining space within said hopper constitutes a button chamber 140 into which buttons are deposited through the open upper end of said hopper. Said recess 139 is formed within the hopper by an enlargement 141 which extends (see Figure 7) from the point 142 adjacent the chute 23 downwardly around the wall of the hopper and upwardly to the point 143 and the space between said two points exposes the periphery of the drum 134 as it is rotated, and it is in this space that the buttons from the bottom of the chamber 140 are fed onto the periphery of the drum preparatory to being discharged into the chute 23. In order to convey the buttons from the bottom of the hopper upwardly towards said space the side of the drum adjacent the chamber 140 has secured thereto a plurality of conveyor elements 144 in the form of diagonally disposed plates each of which will pick up one or more buttons as the drum is rotated and convey the same upwardly towards the point 143. At this point, the portion 141 is provided with inclined surfaces, as indicated at 145, upon which the buttons will be discharged from each conveyor 144 due to the inclination of the latter. The surfaces 145 tend to center the buttons upon the surface of the drum so that each button will come to rest thereon adjacent one of a plurality of button receiving recesses 146 formed in the periphery of the drum. Each recess 146 has its bottom conforming substantially in shape to that of the normal upper surface of the button so that if the button, when

deposited upon the drum, is in an upside down position, it will become seated in one of the recesses, as illustrated in Figure 7. Should, however, a button be right side up on the drum, it will not enter a recess and will be ejected from the surface of the drum, as will later appear, before reaching the chute 23. In other words, only those buttons which become seated in a recess in an upside down position, will be fed from the hopper 10 into the chute so that when the button reaches the delivery position 24, it will be in the right side up position to be transferred to the button clamp of the machine. To aid in guiding a button into one of the recesses as it is deposited upon the drum, the latter carries on its periphery between adjacent recesses small follower lugs 147 which engage a button as the drum rotates. After a button has been seated in a recess and travels towards the delivery chute 23, it is retained in its recess by passing under small leaf springs 148 secured to an adjacent side wall of the hopper 22. The periphery of the drum has formed therein an annular groove 149 which extends centrally through the bottom of the recesses 146 and at the upper entrance end of the chute 23 there is disposed a finger 150 which engages in said groove and beneath a button in one of the recesses 146 so that as the latter is about to be discharged into said chute, said finger will lift 30 the button from its recess so as to facilitate its discharge into said chute. In order to deflect those buttons from the drum which are not in proper position and seated in a recess, there is provided adjacent the entrance to the chute a 35 diagonally disposed deflector plate or baffle 151 arranged in the path of movement of the buttons on the drum and having its lower edge spaced sufficiently from the periphery of the drum to permit those buttons within recesses 146 to 40 pass beneath the deflector or baffle and thus enter the chute to be fed downwardly therethrough by gravity. However, those buttons which have not assumed an inverted position and become seated in the recesses 146 will strike against the baffle 151 and thus be deflected thereby back into the button chamber 140. After a button has passed beneath the baffle 151, it comes in contact with a guide plate 152 (see Figure 10) and the buttons 45 are conveyed diagonally from this point to the entrance of the chute 23. This guide plate 152, by causing the buttons to move in a diagonal direction, provides a means for preventing an excessive number of buttons from entering the chute 23. In other words, should the chute 23 become completely filled, as indicated in Figure 10, the last button 153 to enter into the channel formed by the guide plate 152 will form an abutment for the next succeeding button 154 which is carried beneath the baffle 151 and the latter button striking against the button 153 in an off-center position relative thereto will be deflected from the drum and will fall down into the chamber 140. 50

65 As previously stated, the drum 134 is continuously driven from the pulley 136 by a clutch mechanism 138. This mechanism comprises (see Figure 2) a ratchet 155 fixed upon the shaft 135, and further includes an arm 156 secured to the pulley 136. Pivoted to the outer end of said arm 156 is a pawl 157 having its free end connected to the other extremity of the arm 156 by a coil spring 158 which is of sufficient tension to normally maintain a pin 75 159 on the pawl 157 in engagement with the

ratchet between two of the teeth thereof so that as the pawl is driven by the rotation of the pulley, it will rotate the ratchet and thus revolve the drum 134. However, should a button become temporarily lodged beneath the baffle plate 151, it becomes necessary to dislodge said button so that the drum can continue to rotate and feed other buttons to the chute. Should such a contingency arise, the pulley 136 continues to drive the pawl 157, but the pin 159 will now ride over the teeth of the ratchet 155 and, in so doing, each time said pin is snapped into a recess between two adjacent teeth of the ratchet by the action of the coil spring 158, sufficient vibration will be imparted to the drum 134 to dislodge the jammed button which will then either pass beneath the baffle 151 or be deflected back into the button chamber.

What is claimed is:

1. In a button sewing machine, the combination with a button clamp having horizontally reciprocating movements while a button is being stitched and a vertical movement during which said button is released after the stitching operation, means operable during said vertical movement to actuate said clamp to release said button therefrom and a feeding device having means forming a button delivery position; of a transfer mechanism movable between said position and clamp to deliver a second button to the latter at an intermediate stage of its vertical movement and after the first button has been released.

2. In a button sewing machine, the combination with a button clamp having horizontally reciprocating movements while a button is being stitched and a vertical movement during which said button is released after the stitching operation, means operable during said vertical movement to actuate said clamp to release said button therefrom and a feeding device having means forming a button delivery position; of a transfer mechanism movable between said position and clamp to deliver a second button to the latter at an intermediate stage of its vertical movement and after the first button has been released.

3. In a button sewing machine, a button clamp, a feeding device having means forming a button delivery position, an oscillatory transfer mechanism including a button carrier movable in different planes from said clamp to said position during oscillation of said mechanism to locate said carrier beneath a button at said position, means to alter the plane of movement of said carrier at an intermediate point in its travel between said clamp and said position, means thereupon operable to engage said carrier with said button, means to rotate said carrier and button so that the latter will assume a predetermined position relative to the needle of the machine, and means to move said transfer mechanism from said position to said clamp to deliver said button to the latter subsequent to a stitching operation upon a previous button.

4. In a button sewing machine, the combination with a button clamp having horizontally reciprocating movements while a button is being

stitched and a vertical movement during which said button is released after the stitching operation, means operable during said vertical movement to actuate said clamp to release said button therefrom and a feeding device having means forming a button delivery position; of an oscillatory transfer mechanism including a button carrier movable in different planes from said clamp to said position to locate said carrier beneath and in engagement with a button at said position, means to alter the plane of movement of said carrier at an intermediate point in its travel between said clamp and said position, means to rotate said carrier and button to cause the latter to assume a predetermined position relative to the needle of the machine, and means to move said transfer mechanism from said delivery position to said clamp to engage said button with said clamp at an intermediate stage of the vertical movement of the latter which is subsequent to its release of the first named button.

5. In a button sewing machine, the combination with a button clamp having horizontally reciprocating movements while a button is being stitched and a vertical movement during which said button is released after the stitching operation, means operable during said vertical movement to actuate said clamp to release said button therefrom and a feeding device having means forming a button delivery position; of a transfer mechanism movable between said position and clamp to deliver a second button to the latter while the same is being moved vertically and after the first button has been released, said mechanism including a rotary button-carrying element having pins for insertion into holes of said second button, means to rotate said element and engage said pins in said holes when said mechanism is at said delivery position and before its movement therefrom, and means to control the rotation of said element so that the button rotated thereby will assume a predetermined position relative to the needle of said machine.

6. In a button sewing machine, a button clamp, a feeding device having means forming a button delivery position, an oscillatory transfer mechanism movable between said position and clamp and including a housing having an axial portion about which the housing swings, a button-carrying element rotatable in said housing and having means to engage and rotate a button at said position, means to lower said housing during its movement toward said position so as to locate said button-carrying element beneath the button at said position preparatory to engagement of said rotating means therewith, means including gearing in said housing and a shaft extending through said axial portion to rotate said button-carrying element, and means to control the rotation thereof in such manner that said button will be caused to assume a predetermined position relative to the needle of the machine prior to transfer of the button to said clamp.

7. In a button sewing machine, the combination with a button clamp having horizontally reciprocating movements while a button is being stitched and a vertical movement during which said button is released after the stitching operation, means operable during said vertical movement to actuate said clamp to release said button therefrom and a feeding device having means forming a button delivery position; of a trans-

fer mechanism movable between said position and clamp to deliver a second button to the latter while the same is being moved vertically and after the first button has been released, said mechanism including an oscillatory housing, a rotatable button-carrying element in said housing and having means to engage and rotate said second button while at said position, means to rotate said button-carrying element, and means to control the rotation thereof in such manner that said button will be caused to assume a predetermined position relative to the needle of the machine prior to transfer of the button to said clamp.

8. In a button sewing machine, the combination with a button clamp having horizontally reciprocating movements while a button is being stitched and a vertical movement during which said button is released after the stitching operation, and a feeding device having means forming a button delivery position; of a transfer mechanism movable between said position and clamp to deliver a second button to the latter while the same is being moved vertically and after the first button has been released, said mechanism including an oscillatory housing, a rotatable button-carrying element in said housing and having means to engage and rotate said second button while at said position, means to lower said housing during its movement toward said position so as to locate said button-carrying element beneath the button at said position preparatory to engagement of said rotating means therewith, means to rotate said button-carrying element, and means to control the rotation thereof in such manner that said button will be caused to assume a predetermined position relative to the needle of the machine prior to transfer of the button to said clamp.

9. In a button sewing machine, a button clamp, a feeding device having means forming a button delivery position, an oscillatory transfer mechanism movable between said position and clamp and including a housing having an axial portion about which the housing swings, a button-carrying element rotatable in said housing and having means to engage and rotate a button at said position, a rotatable shaft extending through said axial portion of the housing, gearing connecting said shaft with said button-carrying element to rotate the same when said shaft is rotated, and means to control the rotation of said shaft so that said button will assume a predetermined position relative to the needle of the machine when rotation of said carrying element is stopped.

10. In a button sewing machine, the combination with a button clamp having horizontally reciprocating movements while a button is being stitched and a vertical movement during which said button is released after the stitching operation, means operable during said vertical movement to actuate said clamp to release said button therefrom and a feeding device having means forming a button delivery position; of a transfer mechanism movable between said position and clamp to deliver a second button to the latter while the same is being moved vertically and after the first button has been released, said mechanism including an oscillatory housing having an axial portion, a rotatable button-carrying element in said housing provided with means to rotate said second button while at said delivery position, means to lower said housing prior to reaching said position so as to locate said rotatable element beneath said second button preparatory

5 to its engagement therewith, a rotatable shaft extending through said axial portion, gearing connecting said shaft with said rotatable element, and means to control the rotation of said shaft and button-carrying element so that the button engaged by the latter will be turned and stopped at a predetermined position relative to the needle of the machine.

10 11. In a button sewing machine, the combination with a button clamp having a movement away from the bed plate of the machine which movement is interrupted at an intermediate stage thereof, means to so move said clamp, means to release a sewed button from said clamp before said interruption in its movement, and a feeding device having means forming a button delivery position; of a transfer mechanism movable between said position and clamp, and means to operate said transfer mechanism to deliver a button to said clamp subsequent to the release of the sewed button therefrom and at the moment of interruption in said movement of said clamp.

15 12. In a button sewing machine, the combination with a button clamp having a movement away from the bed plate of the machine which movement is interrupted at an intermediate stage thereof, means to so move said clamp, means to release a sewed button from said clamp before said interruption in its movement, and a feeding device having means forming a button delivery position; of a transfer mechanism movable between said position and clamp, means to operate said transfer mechanism to deliver a button to said clamp subsequent to the release of the sewed button therefrom and at the moment of interruption in said movement of said clamp, said transfer mechanism including a rotary button-carrying element, and means operable while said mechanism is at said delivery position to engage said element with the button thereat so as to rotate the latter to a predetermined position relative to the needle of the machine.

20 13. In a button sewing machine, the combination with a button clamp having a movement away from the bed plate of the machine which movement is interrupted at an intermediate stage thereof, means to so move said clamp, means to release a sewed button from said clamp before said interruption in its movement, and a feeding device having means forming a button delivery position; of a transfer mechanism including a button carrier movable back and forth between said delivery position and clamp and having movements in different planes when approaching said position so as to locate said carrier beneath and in engagement with a button at said position, means to rotate said carrier and button to turn the latter to a predetermined position relative to the needle of the machine, and means to operate said transfer mechanism to deliver said button to said clamp subsequent to the release of the sewed button therefrom and at the moment of interruption in the movement of said clamp.

25 14. In a button sewing machine, the combination with a button clamp having a movement away from the bed plate of the machine which movement is interrupted at an intermediate stage thereof, means to so move said clamp, means to release a sewed button from said clamp before said interruption in its movement, and a feeding device having means forming a button delivery position; of a transfer mechanism including a button carrier movable back and forth between said delivery position and clamp and having movements in different planes when approaching

said position so as to locate said carrier beneath and in engagement with a button at said position, means to rotate said carrier and button to turn the latter to a predetermined position relative to the needle of the machine, means to operate said transfer mechanism to deliver said button to said clamp subsequent to the release of the sewed button therefrom and at the moment of interruption in the movement of said clamp, and means to thereupon continue the movement of said clamp to release said button from said carrier.

15. In a button sewing machine, the combination with a button clamp having a movement away from the bed plate of the machine which movement is interrupted at an intermediate stage thereof, means to so move said clamp, means to release a sewed button from said clamp before said interruption in its movement, and a feeding device having means forming a button delivery position; of a transfer mechanism movable between said position and clamp and including a housing, a button-carrying element rotatable in said housing and having means to engage and rotate a button at said position, means to rotate said button-carrying element, means to control such rotation so that said button will assume a predetermined position relative to the needle of the machine, and means to thereupon move said carrying element from said position to said clamp to engage said button with the latter subsequent to the release of the sewed button therefrom and at the moment of the interruption in the movement thereof.

16. In a button sewing machine, the combination with a button clamp having a movement away from the bed plate of the machine which movement is interrupted at an intermediate stage thereof, means to so move said clamp, means to release a sewed button from said clamp before said interruption in its movement, and a feeding device having means forming a button delivery position; of a transfer mechanism movable between said position and clamp and including a housing,

a button-carrying element rotatable in said housing and having means to engage and rotate a button at said position, means to rotate said button-carrying element, means to control such rotation

5 so that said button will assume a predetermined position relative to the needle of the machine, means to thereupon move said carrying element from said position to said clamp to engage said button with the latter subsequent to the release 10 of the sewed button therefrom and at the moment of the interruption in the movement thereof, and means to return said carrier to said delivery position through a movement in different planes so as to locate the carrier beneath another button at 15 said delivery position.

17. A transfer mechanism for a button sewing machine movable between a feeding device and the button clamp of said machine, said mechanism comprising a housing having an axial portion, a rotatable button-carrying element in said housing having means to engage and rotate a button at said feeding device, a rotatable shaft extending through said axial portion, gearing connecting said shaft with said carrying element, 20 means to rotate said shaft so as to locate said button at a predetermined position relative to the needle of the machine, and means to thereupon move said housing and element to deliver the button carried by the latter to said button clamp.

30 18. In a button sewing machine, the combination with a button clamp, means to feed buttons to said clamp, a control element for said means, a button guiding device spaced from said clamp and having guides for receiving therebetween a sewed button from said clamp at the termination 35 of a sewing operation, a stop member associated with said guides to retain the sewed button in a predetermined position, and means actuated by 40 said control element to retract said stop member to a position to release said button from between said guides.

LAWRENCE G. BURKEY.
